(57) **CLAIM**

The novel ornamental design for a round scare light for a motor vehicle, as shown and described.

DESCRIPTION

FIG. 1 is a front perspective view showing the round scare light for a motor vehicle;

FIG. 2 is a front elevational view of the round scare light for a motor vehicle in accordance with the present invention;

FIG. 3 is a left side elevational view of the a round scare light for a motor vehicle, with an opposite side elevational view being substantially a mirror image;

FIG. 4 is a top plan view of the round scare light for a motor vehicle;

FIG. 5 is a bottom view of the round scare light for a motor vehicle;

FIG. 6 is a back elevational view of the round scare light for a motor vehicle; and,

FIG. 7 is a back elevational view of a recreational vehicle in dotted lines showing the round scare light thereon and a light pattern generates therefrom.

The broken lines in the drawings represent unclaimed environmental subject matter.
